OVERCASTING SEWING MACHINE

Fritz Ebert, Oberndorf-on-the-Neckar
(Wurttemberg), GermanyApplication February 26, 1934, Serial No. 713,034
In Germany March 8, 1933

8 Claims. (Cl. 112—162)

The invention relates to a high speed overcasting sewing machine, i. e. a sewing machine of which the speed of rotation is increased to 5000 revolutions per minute. The technical and economical advantage of the sewing machine according to the invention is that in spite of the increased speed of rotation a considerably thinner or inferior thread can be used than is possible with known machines.

5 Thus, for example, even No. 100 needle threads can be used, and it is even also possible to use wool for the needle thread.

These advantages are attained by a novel needle and looper thread control mechanism. 15 Although hitherto the binding of the seam could be controlled only to a limited extent by means of the thread draw-off lever, it is possible, with the sewing machine according to the invention, to effect control through a wide range by shifting both the oscillatory thread eyes, and adjusting the 20 stationary thread eyes used for control of the thread, in such a manner that the binding may be effected at any desired part or place. On account of the fine degree of adjustment of the 25 action on the threads, a breakage of the thread is to a large extent prevented, and thus a considerable increase in output is attained. The threads are much more gently controlled and thus the causes of the most frequent troubles are avoided 30 from the outset.

The fine control of the needle thread according to the present invention is effected by adjusting two draw-off hooks oscillating in a closed path, while the two looper threads are controlled by a 35 double eye oscillating with the needle lever and a thread eye oscillating with the looper lever. The double eye is longitudinally adjustable for thread control purposes.

40 The draw-off hooks are suitably arranged on the drive link of the needle lever and co-operate with three stationary thread eyes forming a set functioning as two pairs of eyes. The two draw-off hooks so take up the superfluous thread on the withdrawal of the needle from the material and then again on the movement downward of the needle, that a perfect entry of the needle thread into the material is attained. One of the draw-off hooks draws the thread necessary for each 45 stitch from the pre-tensioning means. It is therefore not necessary for the needle to draw the thread from the bobbin or even from the pre-tensioning means, this thread being supplied to it by the two draw-off hooks.

50 To control the looper threads by means of the oscillatory double eye and the thread eye, there is

provided a common initial draw-off and a further thread control. With the initial draw-off located on the front of the machine, the two looper threads run in from both sides, in opposite directions, through stationary thread eyes and are controlled by the thread drawing member actuated by the needle lever and provided with two thread eyes. This member draws thread from the spools when the two loopers move towards the needle, while the thread is released on the 10 return of the loopers.

In the actual thread control also, the two looper threads are controlled by a common member which effects the binding, and this from the lower looper. On the boss of a lever operating this 15 loop is an adjustable ring which carries two adjustable thread eyes which each oscillate between two stationary thread eyes. These thread eyes release thread and take or draw up so much thread as is required by the loopers in their next 20 movement to the needle. Both the oscillating and the fixed thread eyes according to the present invention are adjustable, in order to be able to place the binding at any desired position.

Finally, by the arrangement of a thread 25 protecting tube and a return roller for the upper looper thread, care is taken that this thread is carried to its looper as free from friction or accident as possible.

In the accompanying drawings:—

Fig. 1 is a part sectional front elevation of a 30 sewing machine according to the invention, the table housing being open and unessential parts being omitted.

Fig. 2 is a side elevation of the needle thread 35 control means, and of the looper thread draw-off.

Fig. 3 is a plan view of the mechanism shown in Fig. 2.

Fig. 4 is a plan view of the looper thread 40 control means, and

Fig. 5 is a section through the thread eyes of the looper thread control means.

With respect to the stitch formation and thread binding, the overcasting sewing machine according to the invention is of known character, that is, 45 there are two loopers, a lower looper 1 and an upper looper 2, which co-operate with a needle 3. This is driven by the drive 4 through a link 5 and moved up and down by the usual needle lever 6.

According to the invention, novel cooperating 50 needle thread and looper thread control mechanisms arranged with preliminary draw-off, are provided. The control mechanism for the needle thread 1 consists substantially of two thread draw-off hooks 8 and 9, which co-operate with 55

three stationary thread eyes 10, 11 and 12 through which runs the needle thread 7 (Figs. 2 and 3).

The draw-off hooks 8 and 9 are arranged at the top on the driving link 5 and carry out the movements thereof. By loosening screws 44 (Fig. 2) the hooks 8 and 9 may be adjusted upwardly and downwardly. They are curved and have the shape shown in Fig. 2.

The hooks 8 and 9 are off-center from the upper pin 5a and receive a motion compounded of an arcuate oscillation about the axis of the pin 5a and an up and down reciprocation from the crank 4a through which the drive actuates said link. This motion of the hooks is thus along a looped or closed path.

The three stationary thread eyes 10, 11 and 12 constitute a set functioning as a pair of double eyes and are fitted on a common base plate 13 which, as shown in Fig. 3, is fixed by means of screws 14 on the frame 15 at the rear of the machine.

The draw-off hooks 8 and 9 oscillate between the fixed eyes 10, 11 and 12 and cooperate with them in such manner that when the needle 3 leaves the material, the draw-off hook 8 takes up the needle thread 7 released from the draw-off hook 9, that is, draws it in, by drawing it downwards between the two eyes 10 and 11. At the same time, however, the hook 8 draws the thread from the preliminary tension 38 or from the spool, so that the needle 3 may have supplied to it the thread 7 necessary for each stitch. When the needle 3 has reached its upper turning point, the draw-off hook 8 has come to its lowest point and upon further oscillation gradually releases the needle thread 7. This is now, conversely, so far drawn in and taken up by the draw-off hook 9 as is not required by the downward moving needle 3. Furthermore, on account of the special form of the draw-off hook 9, when the needle 3 has again run past its lowest point the needle thread 7 is still further drawn in, whereby a perfect entry into the work is attained.

The preliminary draw-off of the two looper threads 16 and 17, of which the thread 16 runs to the lower looper 1 and the thread 17 to the upper looper 2, is fitted on the front of the machine on the frame 15, so that both the draw-off and the threads 16 and 17 are easily accessible. The control of the preliminary draw-off takes place from the needle lever 6. To this end, there is arranged on this a further lever arm 18 which carries a rod 19 bent at right angles with two thread eyes 20 and 21, and thus swings up and down with the needle lever 6. This thread draw-off, that is, the double eye 20, 21 swings between two stationary eyes 22, 23 and 22', 23' which are on a rod 24 bent into U-shape which is fixed on the frame 15 of the sewing machine. The two looper threads 16, 17 pass through the stationary eye 22 and 23 to the eyes 20, 21 swinging between them, and then through the eyes 22' and 23' to the thread control means. The two threads 16 and 17 thus run, from opposite sides to the preliminary draw-off as shown in Figs. 1 and 3. This draws threads off the spools when the two loopers 1 and 2 move towards the needle 3, while the threads 16, 17 on the return of the loopers 1, 2 are again released. The eyes 20, 21, 22, 23 and 22', 23' are adjustable. The oscillating double eye carrier 19 may be adjusted axially in the lever arm 18 by loosening the fixing screw 25, and the stationary eye carrier 24 may be adjusted upwardly and downwardly by loosening a fixing screw 28. The latter takes place by the base

plate 26 of the eye carrier 24 being adapted to be moved up and down by means of a vertical slot 27.

The looper thread control is effected by the movement of a member which directly undertakes the binding of the threads. In the example shown, the boss 36 of the looper lever 37 of the lower looper 1, is used for this (Figs. 1 and 4), and the control of the two threads 16 and 17 is carried out by two oscillating eyes 29 and 30 which each co-operate with two stationary eyes 10 31 and 32. The oscillating eyes 29 and 30 are on arms 33 and 34 which are fitted on a ring 35 fastened on the boss 36 of the lower looper 37. The lower looper thread 16 passes through the stationary eyes 31 and the intermediate eye 29, 15 which oscillates up and down between the two eyes 31 and runs to the bottom looper 1, while the upper looper thread 17 runs through the fixed eyes 32 and the intermediate eye 30, which oscillates up and down between the eyes 32, and 20 then to the top looper 2.

The control takes place by the two oscillating thread eyes 29 and 30 releasing amounts of thread required by the loopers 1 and 2 when these move towards the needle 3. On the return of the 25 loopers 1, 2, on the contrary, the surplus thread is again taken up and at the same time so much thread is drawn off through the thread tensioning discs 39 as the two loopers 1 and 2 again require on the next movement.

The thread eyes 29, 31 and 30, 32 are adjustable. Thus the oscillating eye holders 33, 34 can be axially adjusted after loosening the fixing screws 39, and the stationary eyes 31, 32 can be adjusted laterally. The latter takes place by means of a common slot 40 and two fixing screws 41.

The bottom thread 16 runs from the stationary eyes 31 through a protecting tube 42, at the outlet end of which and at the turning point of the bottom thread 16 there is a loose guide roller 43.

I claim:

1. In an overcasting sewing machine with two loopers cooperating with a needle and levers for oscillating the needle and loopers, thread control mechanism comprising a pair of draw-off hooks operative on the thread supplied to the needle, means for oscillating said hooks in a closed path, means for adjusting the draw-off hooks in said oscillating means, a double eye acting upon the threads supplied to the two loopers, means for oscillating the double eye from the needle lever, separate thread eyes acting on the looper threads, and means for oscillating the separate thread eyes from the looper lever.

2. In an overcasting sewing machine with two loopers cooperating with a needle and levers for oscillating the needle and loopers, thread control mechanism comprising a pair of draw-off hooks operative on the thread supplied to the needle, means for oscillating said hooks in a closed path, a set of three stationary eyes traversed by the needle thread arranged with the two draw-off hooks oscillating in the spaces between said stationary eyes, means for adjusting the draw-off hooks in said oscillating means, a double eye acting upon the threads supplied to the two loopers, means for oscillating the double eye from the needle lever, separate thread eyes acting on the looper threads, and means for oscillating the separate thread eyes from the looper lever.

3. In an overcasting sewing machine with two loopers cooperating with a needle and levers for oscillating the needle and loopers, thread control

mechanism comprising a pair of draw-off hooks operative on the thread supplied to the needle, means for oscillating said hooks in a closed path, means for adjusting the draw-off hooks in said oscillating means, a double eye acting upon the threads supplied to the two loopers and forming a preliminary draw-off for the looper threads which run to said double eye from opposite sides, means for oscillating the double eye from the 10 needle lever, separate thread eyes acting on the looper threads, and means for oscillating the separate thread eyes from the looper lever.

4. In an overcasting sewing machine with two loopers cooperating with a needle and levers for 15 oscillating the needle and loopers, thread control mechanism comprising a pair of draw-off hooks operative on the thread supplied to the needle, means for oscillating said hooks in a closed path, means for adjusting the draw-off hooks in 20 said oscillating means, a double eye acting upon the threads supplied to the two loopers, means for oscillating the double eye from the needle lever, separate thread eyes acting on the looper threads, means for oscillating the separate thread eyes 25 from the looper lever, and pairs of stationary eyes, each pair cooperating with the two said oscillatory separate eyes.

5. In an overcasting sewing machine with two loopers cooperating with a needle and levers for 30 oscillating the needle and loopers, thread control mechanism comprising a pair of draw-off hooks operative on the thread supplied to the needle, means for oscillating said hooks in a closed path, means for adjusting the draw-off 35 hooks in said oscillating means, a double eye acting upon the threads supplied to the two loopers, means for oscillating the double eye from the needle lever, separate thread eyes acting on the looper threads, means for oscillating the separate thread eyes from the looper lever, and a ring carrying the separate thread eyes 40 and adjustable relatively to the fulcrum of the looper lever.

6. In an overcasting sewing machine with two loopers cooperating with a needle and levers for 45 oscillating the needle and loopers, thread con-

trol mechanism comprising a pair of draw-off hooks operative on the thread supplied to the needle, means for oscillating said hooks in a closed path, means for adjusting the draw-off hooks in said oscillating means, a double eye 5 acting upon the threads supplied to the two loopers, means for oscillating the double eye from the needle lever, separate thread eyes acting on the looper threads, means for oscillating the separate thread eyes from the looper lever, and 10 pairs of stationary eyes, each pair cooperating with the two said oscillatory separate eyes, and said pairs of stationary eyes being laterally adjustable.

7. In an overcasting sewing machine with two 15 loopers cooperating with a needle and levers for oscillating the needle and loopers, thread control mechanism comprising a pair of draw-off hooks operative on the thread supplied to the needle, means for oscillating said hooks in a 20 closed path, means for adjusting the draw-off hooks in said oscillating means, a double eye 25 acting upon the threads supplied to the two loopers, means for oscillating the double eye from the needle lever, separate thread eyes acting on the looper threads, means for oscillating the separate thread eyes from the looper lever, and 30 pairs of stationary eyes, each pair cooperating with the two said oscillatory separate eyes, said pairs of stationary eyes being laterally adjustable 35 and mounted in a common groove in the frame of the sewing machine.

8. In an overcasting sewing machine with two loopers cooperating with a needle and levers for 40 oscillating the needle and loopers, thread control mechanism comprising a pair of draw-off hooks operative on the thread supplied to the needle, means for oscillating said hooks, means for adjusting the draw-off hooks in said oscillating means, a double eye 45 acting upon the threads supplied to the two loopers, means for oscillating the double eye from the needle lever, separate thread eyes acting on the looper threads, and means for oscillating the separate thread eyes from the looper lever.

FRITZ EBERT. 45
